UNITED STATES PATENT OFFICE.

FRANK J. LE CLAIR, OF ATTLEBORO, MASSACHUSETTS, ASSIGNOR TO FREEMAN-DAUGHADAY COMPANY, OF CHARTLEY, MASSACHUSETTS, A CORPORATION OF MASSACHUSETTS.

HOLDER FOR COLLARS.

1,392,582.

Specification of Letters Patent.

Patented Oct. 4, 1921.

Application filed May 17, 1921. Serial No. 470,359.

To all whom it may concern:

Be it known that I, FRANK J. LE CLAIR, a citizen of the United States of America, and resident of Attleboro, in the county of 5 Bristol and State of Massachusetts, have invented new and useful Improvements in Holders for Collars, of which the following is a specification.

This invention concerns collar holders for 10 retaining soft collars in properly adjusted position, and relates more especially to the resiliently extensible or adjustable type of collar holder which permits the separation of the corners of the collar in response to 15 movements of the wearer and subjects them to tension tending to draw them toward one another.

The object of the present invention is to 20 improve devices of the above character whereby to simplify the construction thereof, and decrease the cost of production, while at the same time providing collar gripping and tensioning means which shall be effective for the purpose intended.

25 A preferred embodiment of means for attaining the object of the invention is illustrated in the accompanying drawings in which,—

Figure 1 is a top plan view of the complete device;

30 Fig. 2 is a similar view showing the front guide bar in horizontal, longitudinal cross section;

Fig. 3 is a front elevation of one of the 35 collar gripping devices employed; and

Fig. 4 is a transverse cross section on a line such as *a*, *b*, of Fig. 2.

The holder comprises an elongated bar 1 which may, if desired, be somewhat curved, 40 or of arcuate form, from end to end.

This bar preferably consists of a strip of sheet material suitably bent to form the front wall 2 and the parallel top and bottom walls 3, 4. The free edges of the walls 45 3, 4, may be inwardly bent as indicated at 5, 6, whereby the structure takes the form of a substantially rectangular tube, leaving, if desired, a longitudinal slot between the parts 5, 6.

50 The clamping devices, which are of duplicate construction, each preferably consists of a strip of metal comprising the middle member 9, which forms one of the clamping elements, such member being bent at one

end as indicated at 9^a and being continued 55 to form the oppositely disposed clamping member 10. The other end of member 9 is also bent at 11 in a reverse direction to provide the sliding member 12 which lies substantially parallel to the member 9, and 60 is spaced therefrom such distance as to produce a close sliding fit between the clamping device and the guide bar. The members 9 and 12 are curved longitudinally on arcs of substantially the same curvature as that 65 of the bar 1.

The member 10 is preferably provided with a gripping portion 13 of substantial length which conforms in shape generally to the adjacent surface of the member 9, 70 and such portion 13 may, if desired, be roughened whereby to increase its gripping action upon the material.

Extending from the end of the member 13 there is provided a finger 14 which diverges from the member 9 whereby to form 75 a guiding mouth for the reception and guidance of the edge of the collar to facilitate the insertion of the latter between the members 13 and 9.

At a point adjacent its free extremity, the slide member 12 has an outstanding lug 15, which may be formed, if desired, by striking up the material from the opposite side. Coöoperating with this lug to limit the outward movement of the clamping device is an 85 end wall 16^a formed integrally with the member 2 of the bar and extending inwardly across the open end of the tubular bar.

The free end of the slide member 12 is 90 provided with an opening 16 therethrough, and leading to such opening from one edge of the member 12 is an oblique slot 17, thus forming a hook-like member 17^a. At 18 is indicated a coil tension spring provided 95 at its opposite extremities with closed loops 19, 20, respectively.

In assembling the device, one of the loops, as for example that designated at 19 is passed through the slot 17 and into the opening 16 of the gripping device 8. If desired, the hook 17^a of the member 12 may now be pressed inwardly whereby to decrease the width of the slot and prevent the removal of the spring loop therefrom. The spring 100 is now inserted in the opening at one end of the tubular bar, the part 16^a at this time 105 extending substantially in alignment with

part 2, and the member 12 of the gripping device 8 is also inserted in such opening, the member 9 thereof extending along the outer side of the tubular bar and lying closely adjacent thereto.

By means of a suitable instrument which may be inserted at the opposite end of bar 1 or into the slot between the edges 5, 6, the other loop 20 of the spring may now be drawn out beyond the end of the tubular bar and the hook 17^a of the other gripping device 7 may be inserted therein, the slot 17 then being closed by pressure if desired. The spring is now permitted to contract, while at the same time the member 12 of the gripping device 7 is permitted to pass into the opening in the end of the bar. The spring, together with the members 12 of the respective gripping devices, is thus positioned within the bar and concealed thereby, and the members 16^a of the bar are turned downwardly to lie in the position indicated in Figs. 1 and 2. With this arrangement the members 16^a serve as stops to limit outward movement of the members 12, and also close the ends of the tubular bar 1, while the single tension spring serves to urge the gripping devices toward each other. By the provision of the elongated clamping surface at 13, a very secure grip may be secured upon the material of the collar, while the arrangement of the members 9 and 12 in substantial parallelism serves properly to support and guide the gripping devices whereby binding of the same is substantially eliminated.

While the bar has been illustrated as of curved form, it is evident that it might well be made straight from end to end if desired, and while for convenience in manufacture the bar has been shown as formed by bending a piece of sheet material, it is evident that a continuous tubular bar might well be employed. It is also clear that other arrangements of clamping elements might well be substituted for those herein disclosed without in any manner departing from the spirit of the invention.

Having thus described the invention in a preferred embodiment of the same together with the mode of use thereof, what I claim and desire to secure by Letters Patent of the United States is:

1. A collar holder comprising a gripping device having opposed clamping members and a slide member, said latter member having an opening therethrough adjacent one extremity and an oblique slot extending from the edge of said member to the open-

ing, and an actuating spring having a loop element at one of its extremities passing through said opening.

2. A collar holder comprising a tubular bar, and a pair of gripping devices supported thereby, each of said gripping devices comprising a pair of substantially parallel members constructed and arranged slidably to engage the inner and outer surfaces of said bar respectively whereby to be guided thereby, and spring means normally tending to move said clamping devices in opposite directions.

3. A collar holder comprising a tubular bar, a pair of collar gripping devices each having an elongated member slidably engaging the inner wall of the bar, the adjacent ends of said members being spaced apart, and a tension spring interposed between said ends and connecting said members.

4. A collar holder comprising a tubular bar, and a collar gripping device comprising substantially parallel elements disposed within and without the bar respectively, said elements being so spaced as to engage the intervening wall of the bar with a close sliding fit.

5. A collar holder comprising a bar, a collar gripping device having a pair of substantially parallel guide elements for engagement with said bar, one of said elements being provided with a projecting stop lug engageable with a part projecting from the bar and with an opening for the attachment of actuating means for such elements.

6. A collar holder comprising a bar, a collar gripping device consisting of a narrow strip of sheet material having opposed collar gripping surfaces and a guide element, slidably engaging said bar and an outstanding stop lug struck up from one side of said guide element and engageable with a part projecting from the bar.

7. A collar holder comprising a tubular bar having flaps partially closing its ends, collar gripping devices having guide elements slidably engaging the interior wall of said tube, said devices entering the opposite ends of the tube through the spaces to one side of said flaps, stop lugs projecting from said elements and engageable with the inner sides of the respective flaps, and a tension spring within the bar and uniting said elements.

Signed by me at Attleboro, Massachusetts, this 9th day of May, 1921.

FRANK J. LE CLAIR.
